UNITED STATES PATENT OFFICE

2,094,749

ROTARY MACHINE FOR DYEING AND WASHING TEXTILE MATERIALS

Juan Rabassa, Barcelona, Spain

Application July 19, 1933, Serial No. 681,053
In Spain April 26, 1933

2 Claims. (Cl. 8—19)

The machine according to the invention is of special application in the dyeing and the washing of textile materials especially stockings, skeins and other small articles; it has a rotary action and comprises a central reservoir for the dyeing liquid or for the washing or other liquid to be used in the treatment, and radially disposed containers provided with valves in corresponding positions to establish or break communication between the said containers and the central reservoir. The materials to be treated in the baths of treating liquid are introduced into the radially disposed containers.

The rotary movement of the central reservoir with its radially disposed containers causes the textile materials to be continuously and thoroughly washed or stirred in the liquids in the containers in the treatment, the thoroughness of the washing or stirring of the textiles with the treating liquid determining the efficacy of the treatment.

A machine constructed according to the invention, is diagrammatically illustrated by way of example in the accompanying drawings.

Figure 1 is a front elevation of the machine according to the invention.

Figure 2 is a corresponding side sectional elevation.

Figure 3 is a detail view on an enlarged scale in section of one of the radially disposed containers.

The machine comprises two frame members 1 and 2, supporting at their upper ends bearing blocks 3 and 4 on which a tubular shaft 5 pierced with holes 6 is mounted to rotate. A reservoir 7 for the treating liquid is formed integral with a tubular shaft 5 to rotate with it, and carries secured thereto containers 8, 9, 10, 11, 12, and 13 which are radially disposed with respect to the tubular shaft 5. The containers hereinbefore mentioned are secured to the central reservoir 7 by means of draw bolts such as 14, 15 (Figure 3). Each of the containers 8, 9, 10, 11, 12, and 13 is fitted with a metallic gauze filter 16 and, moreover is provided with a valve 18 fitted in an opening 17 and operated by the aid of an eccentric 19, a spring 20 being provided on the valve stem to ensure that the valve stem bears against the eccentric. Each eccentric 19 is mounted on a transverse arm or spindle 21 with which there is integrally formed an angle arm member 22. On the fixed part of the machine are disposed two projecting abutments 23 and 24, for co-operating with the angle arm members 22 to open and close the valves 18. The

abutments 23 and 24 may be put out of action when desired with respect to the arm members 22 by being withdrawn in a direction away from the machine. 25 is the receiver containing the dyeing liquid or other liquid which is raised to pass through a pipe 26 under the action of a pump 26' through the tubular spindle 5 into the central reservoir 7 through the holes 6. The water necessary for the formation of the bath with the said dyeing liquid or other liquid may be introduced through the pipe 28. Through the pipe 27 steam is also led to the central reservoir 7 for heating the bath and for producing a pressure adapted to favour the treatment of the articles.

Each container such as 8 comprises an atmospheric valve 29 which operates to prevent the formation of a vacuum, when the steam contained in the container 8 is condensed. The valve 29 is provided in a dome-shaped cover 32 by which the container 8 is closed in the use of two wing nuts such as 30, 31 applied on the extremities of the draw bolts 14, 15.

The rotary reservoir 7 comprises, moreover, three pipes 33, 34, and 35 leading from the machine and provided with cocks 36, 37, and 38 respectively, operated by angle arm members 39, 40, and 41, by means of end pins 42, 43 which may be rendered inoperative by withdrawal in a direction away from the machine.

After having filled the containers 8, 9, 10, 11, 12, and 13 with the articles to be dyed or to be washed, by opening the covers 32 and closing them as soon as the articles have been put in, and after having introduced the treating liquid into the central reservoir 7, the reservoir 7 with the radially disposed containers 8, 9, 10, 11, 12, 13 is rotated; the valves 18 will remain open so that the radially disposed containers may be in communication with the central reservoir. This result is obtained by placing the abutment 23 in the operative position and the abutment 24 in the inoperative position, the radially disposed containers will then fill with liquid when they take up the position with the openings 17 uppermost, and will empty successively when they take up the position with the openings 17 downwardly directed. In this way the effect will be obtained that during the operation of the machine, liquid is passed into and out of the radial containers and a thorough stirring of the liquid with the articles being treated takes place, which will effectively dye or wash the articles, in the use of only a small quantity of treating liquid, this being one of the principal advantages of the machine.

When, the treatment being finished, it is desired to empty containers 8, 9, 10, 11, 12, and 13 and to stop the flow of liquid into them from the central reservoir 7, the valves 18 will have to be 5 opened when the containers are uppermost with the openings 17 downwardly directed and closed when the containers are in the opposite position; this is effected by placing both the abutments 10 23 and 24 at the same time in the operative positions.

The pipes 33, 34, and 35 serve to permit the escape of steam from the reservoir 7 when it is desired to lower the pressure in the same and for this purpose the pins 42 and 43 are placed 15 in the operative position, then the cocks 36, 37, and 38 are open when the angle arm members 39, 40, and 41 abut against the pin 42, and close when the pin 43 bears against them, the steam passing out to the atmosphere during the travel 20 from the pin 42 to the pin 43, that is to say, during the desired number of revolutions. These pipes 33, 34, and 35 also serve to empty 25 of liquid the central reservoir 7 when the treatment is ended and for this purpose the cocks 36, 42 in the operative position and the pin 43 in 30 the inoperative position.

At 44 is provided a sample container for introducing a sample of the article being treated, 35 which is withdrawn when the result has been observed before withdrawing the articles from the containers 8, 9, 10, 11, 12, and 13 by the corresponding openings in the covers.

In the containers are provided transverse rods 35 such as 45, 46 adapted to serve as deflectors of the articles introduced into the containers so that they may be subjected to violent changes of position to render more effective the application 40 of the treating liquids during the rotary movement of the containers.

The machine hereinbefore described affords the advantage, as has been hereinbefore mentioned, that the dyeing or washing is effected in the use of a small quantity of treating liquid, as this is mixed distributively on the article under treatment when the liquid is passed successively in and out of the radial containers. 5

I claim:

1. A rotary machine for dyeing and washing textile materials with fluids, comprising a central liquid supply and exchanging reservoir, a series of containers for receiving and treating the materials in the fluids radially disposed with respect to the central reservoir and mounted thereon to rotate with it, said containers having 10 openings communicating with the central reservoir, valves in the said containers for closing the openings, eccentrics secured on spindles mounted on the containers to co-operate with the valves, angle arm members secured on the eccentric spindles and adjustable stops mounted on the machine frame for co-operating with the angle arm members to open and close the valves. 15

2. A rotary machine according to claim 1, in which a tubular rotary shaft supports the central reservoir, and in which pipes for the supply of steam to the said reservoir and for emptying and putting into communication the said reservoir with the atmosphere are connected to the said reservoir, said machine being also provided 20 with cocks by means of which said reservoir emptying pipes are controlled, angle arm members connected to and operating said cocks, the cocks and the angle arm members being mounted 25 on the reservoir emptying pipes and rotatable therewith, and adjustable stops mounted upon the fixed frame parts of the machine for co-operating with the angle arm members to open and close the said cocks. 30
